IRVING WRIGHT, OF BALTIMORE, MARYLAND.

DRAFT-GEAR.

1,115,760.

Specification of Letters Patent. Patented Nov. 3, 1914.

Application filed August 14, 1912. Serial No. 714,990.

To all whom it may concern:

Be it known that I, IRVING WRIGHT, a citizen of the United States of America, residing at the city of Baltimore, State of Maryland, have invented certain new and useful Improvements in Draft-Gears, of which the following is a specification.

The object of this invention is to provide a draft rigging for ears of a new and improved construction of increased simplicity, efficiency and length of life.

The invention relates particularly to draft gears of the type comprising a shock-absorbing member and a yoke with transverse keys which fit in registering slots in the yoke and sills or draft beams. Such draft gears as used prior to my invention may be divided into two classes, those having three keys, the rear key acting as a rear stop in buffering, *i. e.*, in which the rear key serves to transmit to the draft beams the thrust applied to the shock-absorbing member in buffering, and those in which there are two keys only, the rear stop being in the form of a stationary member which transmits to the frame the thrust applied to the shock-absorbing member in buffering. In some instances, the rear arm of the yoke bears against this rear stop and transmits the buffering pressure to the stop. In the production of these draft gears the rear stop to which I have referred, and likewise the third key, which in the three key draft gear takes its place, with the bearing therefor in the check plate, are supplied at an expense which is a considerable proportion of the cost of the whole draft gear, and the object of the present invention is to provide a draft gear which shall have neither the third key, nor the rear stop to which I have referred, and which is therefore capable of being produced at a cost much less than that of either of the regular two or three key types.

The device of my invention, in its preferred form, consists of a draft gear having a yoke and the usual shock-absorbing device, the motion of the yoke relatively to the draft beams being limited so that the yoke is placed under tension both in buffering and drawing, and in both instances receives and transmits the stress applied to the yielding or shock-absorbing member.

In the preferred form of my invention, I use as a means for limiting the motion of the yoke, a stationary key which in effect serves both as a front and as a rear stop

whereby the usual third key and rear stop are eliminated, but it is within the scope of my invention to employ other means to this end.

In the accompanying drawing I have illustrated a draft gear embodying the features of my invention in their preferred form.

Figure 1 is a view, half in horizontal section and half in top plan. Fig. 2 is a central vertical section.

As shown, the device consists of draft beams 1, having elongated front slots 2 and rear slots 3. In the front slots is a key 4 mounted to slide therein, and in the rear slots is a key 5 which fits the slots and is stationary. Between the draft beams is a yoke 6 having an elongated slot 7 to receive the front key and an elongated slot 8 for the rear key. The length of the front slots in the yoke and their position relatively to the rear slots and the corresponding slots in the draft beams is such that the arms of the yoke cannot be placed under compression. Between the arms of the yoke at the front end is the draw-bar 9 slotted at 10 to receive the forward key 4 which thus connects the draw-bar to the yoke. Mounted on the rear key 5 is a follower 11 which is provided with an elongated slot 12 to receive the key, the follower having sufficient play relatively to the key to permit the buffering stress to be transmitted thereby from the draw-bar to the shock-absorbing member 13 which may be placed within the yoke, taking a bearing at its front end at 14 on the follower and at its rear end on the rear arm 15 of the yoke or on the filler plate 16 seated on the rear arm of the yoke. Straps 17 and 18 support and hold the yoke and resilient member 13 in place. The yoke as shown is unsupported from the rear, and its motion is limited by the key 5. In the normal position of the yoke, the front ends of the slots 8 bear against the front face of the key 5. At the same time the rear end of the follower slot bears against the rear face of the key 5, the front face of the follower engages the rear end of the draw-bar, and the front key is in the center of slots 2 in the beams. This position of the parts is maintained by the spring under condition of no stress.

The operation of the device, when tension is applied to the draw-bar, will be easily understood. The tension is communicated by the front key 4 directly to the yoke and

by the yoke, through its rear arm 15 and plate 16, to the spring or shock-absorbing member 13 which transmits the drawing stress to the follower 11, and thence to the 5 rear key 5, which is stationary and rigid and transmits the drawing stress directly to the draft beams. In buffing, the compression stress in the draw-bar is applied directly to the follower 11. It is transmitted 10 thereby to the spring or shock-absorbing member 13, and thence to the rear arm 15 of the yoke. As the yoke is unsupported from the rear, that is, as there is no rear stop on the frame, and normally, *i. e.*, in condition 15 of no stress; the front ends of the slots 8 in the yoke bear against the front edge of the key 5 so the yoke cannot move to the rear from normal position, the buffing pressure applied to the yoke sets up a tension stress 20 in the yoke, and this stress is transmitted directly to the key 5, and hence to the frame of the car. Thus the key 5 limits the movement of the yoke and serves as a front and rear stop so that the usual rear stop or third 25 key is dispensed with and the draft gear is materially cheapened.

It will be apparent that within the scope of my invention various other means may

be utilized for limiting the motion of the yoke so that it is placed under tension both 30 in drawing and in buffing and the rear stop becomes unnecessary.

I have described specifically a single embodiment of my invention in order that its nature and operation may be clearly understood. However, the specific terms herein 35 are used in their descriptive rather than in their limiting sense and the scope of the invention is defined in the claim.

I claim—

In a draft gear, in combination, a fixed key, a yoke slotted to receive the key and mounted to move forwardly and held from rearward movement by said key, a resilient member within the yoke between said key 45 and the rear end of said yoke, and means for applying both drawing and buffing stresses to the yoke whereby such stresses are transmitted to the fixed key so the single fixed key acts as a front and rear stop. 50

Signed by me at Baltimore, Maryland, this 12th day of August, 1912.

IRA ORVILLE WRIGHT.
